UNITED STATES PATENT OFFICE.

JOHN B. BAXTER, OF TROY, NEW YORK, ASSIGNOR TO COVERT MANUFACTURING COMPANY, OF WATERVLIET, NEW YORK, A CORPORATION OF NEW YORK.

COMBINED HARNESS SLIDE AND SNAP.

Application filed June 14, 1927. Serial No. 198,753.

This invention relates to improvements in combined harness slides and snaps of the type comprising a slide to receive and slidably engage the breast connection, strap, chain or 5 the like, of double harness, and an attaching snap pivotally connected to the slide and adapted to receive the neck yoke eye.

The object of the invention is to provide an improved combined harness slide and snap 10 of simple, inexpensive construction that will operate smoothly and easily, and will be strong, durable, reliable and efficient in use.

Particularly important novel characteristics of the invention reside in the special construction of slide, the particular connection of the slide to the attaching snap, and in the special means provided for limiting the oscillatory movement of the slide relatively to the attaching snap, whereby strain and wear on 20 the parts is materially reduced, and ease of operation, strength, durability, and efficiency secured in a simple inexpensive structure.

The invention, with other objects and advantages thereof, and the particular construction, combination and arrangement of parts comprising the same, will be understood from the hereinafter contained detail description, when considered in connection with the accompanying drawings, forming part hereof, 30 and illustrating one embodiment of the invention.

In the drawings:

Figure 1 is a side elevation of a combined slide and snap constructed in accordance with 35 the present invention.

Fig. 2 is a top plan view.

Fig. 3 is a section on the line $x-x$ of Figure 2, part of the attaching snap being shown in side elevation.

40 Fig. 4 is a side elevation of a modified construction.

Fig. 5 is a plan view of the modified construction illustrated in Figure 4, and

Fig. 6 is a section on the line 6-6 of Figure 45 5, part of the device being shown in elevation.

While particular embodiments of the invention are illustrated in the drawings, it will of course be understood that changes and variations in the particular constructions 50 shown, may be made and the invention embodied in other forms, as will appeal to those skilled in the art and falling within the scope of the appended claims, without departing from the spirit of the invention.

Referring to a detailed description of the 55 particular embodiment of the invention illustrated in Figures 1, 2 and 3 of the drawings, the slide, designated generally A, of the device comprises a body portion 1 rounded or curved longitudinally, and provided with 60 side walls or marginal flanges 2 at its under side, the structure being of channel like form to slidably receive within the same a breast connection. The side walls or marginal flanges 2, which are shown substantially 65 semi-circular shape in form, are co-extensive with the body portion 1, said flanges or side walls being of greatest depth at the central part of the body portion 1 and gradually decreasing in height toward either end thereof. 70 In addition to its longitudinal curvature, the slide A is curved transversely, being concave at its underside, the bottom face 3 of the body portion 1 of the slide merging into the inner side faces 4 of the side walls or flanges 2 in 75 a gradual curve, the particular construction of slide shown, being especially adapted for use with a breast connection in the form of a chain, the structure possessing strength and being such as to prevent binding or 80 cramping, and providing for free sliding engagement of the links of the chain with the slide, the bottom face 3 and the inner side faces 4 of the side walls or flanges 2 of the slide being smooth, and the flanges 2 at their 85 edges and the ends 5 of the body portion 1 being rounded, the ends of the body portion joining the ends of the flanges 2 in a gradual curve, as shown. At its upper side 6 the slide has a projecting portion or boss 7, which is 90 provided with an aperture or bore 8 to form a bearing located above its bottom chain engaging surface 3, said boss extending transversely coextensive with the body portion 1 and being provided with enlarged end portions 9 having flat end faces.

The attaching snap member comprises a hook portion 10, a spring held pivoted tongue 11 and a shank 12. Integral with the shank 12 is a rectangular shaped frame comprising 100 spaced side arms 13, and forward and rear cross bars 14, 15, the shank 12 connecting with the cross bar 15. Intermediate their ends the side arms 13 have rounded enlarged apertured portions 16.

The slide A is adapted to be arranged between the side arms 13 with its boss 7 disposed in alignment with the enlarged aper-

tured portions 16 of the side arms 13, and the slide is pivotally connected to the side arms 13 by a rivet 17 or equivalent fastening member extending transversely through the apertures of the enlarged portions 16 of the arms 13 and the aperture 8 of the boss 7 of the slide, said rivet having headed ends to engage the outer side faces of the side arms 13.

The diameter of the aperture or bore 8 of the boss 7 is slightly greater than the diameter of the rivet 17 so that the slide is adapted to rock freely upon the rivet, the end faces of the enlarged end portions 9 of the boss 7 of the slide A slidably engaging the inner 15 side faces of the enlarged portions 16 of the side arms 13.

The rear cross bar 14 of the attaching snap is adapted to serve as means for limiting the oscillatory movement of the slide A in either 20 direction relatively to the attaching snap, the same being arranged in the path of movement of and adapted to be engaged by the outer end portions of the slide at the upper side thereof. As will be understood by 25 changing the point of the pivotal connection of the curved slide relatively to the cross bar or changing the size of the bar, the angle at which the slide will be stopped by the bar may be adjusted as desired.

30 The attaching snap including the hook portion 10, shank 12, and rectangular frame 13, 14, 15, is cast or otherwise suitably formed in a single piece or unit, and the slide A preferably takes the form of a casting.

35 In the modified construction illustrated in Figures 4, 5, and 6 of the drawings, the construction of the slide is the same and the slide is pivotally connected at a point above its under chain engaging side to and between 40 the side arms of the snap like in the construction illustrated in Figures 1, 2, and 3, hereinbefore described, this modified construction possessing all of the advantages of the particular construction of slide and the 45 special pivotal connection of the same to the snap at a point above its under chain engaging side. In this particular instance, however, the frame of the snap is not provided with a rear cross bar or with special means 50 for limiting the oscillatory movement of the slide, the slide being pivotally mounted closer to the forward cross bar of the snap, and the breast chain itself depended upon to limit the oscillatory movement of the slide 55 in the operation of the device. In Figures 4, 5, and 6, 18 designates the slide having at its upper side the projecting portion or boss 19 to provide a bearing above its bottom chain engaging surface 20. The slide 60 18 is pivotally connected to the attaching snap 21 by a rivet or similar fastening member 22 extending through the aperture of the boss 19 of the slide and through the apertures of the enlarged portions 23 of the side arms 65 24 of the frame of the snap 21. In this con-

struction, the distance of the pivotal mounting of the slide 18 from the cross bar 26 of the frame of the snap 21 is such that the chain 27 will engage the cross bar 26 of the snap frame and in a way act to limit the oscillatory movement of the slide in either direction. 70

It will be noted that by the particular construction and arrangement of parts hereinbefore set forth a combined slide and snap 75 is afforded, which is of a simple, strong, durable, efficient nature and which can be manufactured at low cost. The particular construction of slide and the special mounting or pivotal connection of the same to the attaching snap acts to secure ease and smoothness in operation, avoiding wear and strain on the parts, and the particular means provided for limiting the movement of the slide 80 relatively to the attaching snap being of a simple, efficient nature. 85

What I claim is:

1. In a device of the class described, the combination of a slide adapted to receive a chain or the like at its under side, an attaching snap having rearwardly extending spaced side arms, and means pivotally connecting the slide intermediate its ends to and between the side arms of the snap, said arms of the snap and said slide having portions 95 cooperating to limit the extent of oscillatory movement of the slide in either direction relatively to the attaching snap. 95

2. In a device of the class described, the combination of a slide adapted to receive a chain or the like at its under side, an attaching device having spaced rearwardly extending side arms and a cross bar connecting said arms at their rear end portions, and means pivotally connecting the slide intermediate its ends to and between said arms in rear of said cross bar, the cross bar being disposed in the path of movement of the end portions of the slide and serving as a guard to limit the extent of oscillatory movement of the slide in either direction relatively to the attaching means. 100

3. In a device of the class described, the combination of a slide comprising a curved plate portion adapted to receive a chain or the like at its under side, and having an apertured boss at its upper side intermediate its ends, said boss extending transversely coextensive with the width of the slide, an attaching device having spaced side arms provided with oppositely disposed apertures, and means pivotally connecting the slide to and between the side arms for rocking movement relatively to the attaching device, said means comprising a pin extending transversely through the apertured boss of the slide and the apertures of the side bars and secured thereto, the end faces of said boss forming bearings to engage the side bars. 110 115

4. In a device of the class described, the 120

combination of a slide adapted to receive a chain at its under side, said slide comprising a longitudinally curved plate portion transversely concave and provided with substantially semi-circular shaped side flanges at its under side extending co-extensive therewith, said flanges gradually decreasing in height from the center of the plate toward either end thereof, and said slide having a part projecting from its upper side intermediate its ends, an attaching device having spaced side arms, and means pivotally connecting the slide at the part thereof projecting above its upper face to and between said arms for rocking movement relatively to the attaching device.

5. In a device of the class described, the combination of a slide adapted to receive a chain or the like at its under side, an attaching snap having rearwardly extending spaced side arms, means pivotally connecting the slide intermediate its ends to and between the side arms of the snap inwardly of the rear ends thereof, and means on the 20 side arms located at a point above the pivotal connection of the slide to said arms disposed in the path of movement of the end portions of the slide and serving to limit the extent of oscillatory movement of the slide

in either direction relatively to the attaching snap.

6. In a device of the class described, the combination of a slide adapted to receive a chain or the like at its under side, said slide comprising an elongated plate portion curved longitudinally and transversely, said plate portion being concave at its under side, an attaching device having spaced rearwardly extending side arms, and means pivotally connecting the slide intermediate its ends to and between said arms.

7. In a device of the class described, the combination of a slide adapted to receive a chain or the like at its under side, said slide comprising a longitudinally curved plate portion with substantially semi-circular shaped side flanges at its under side coextensive in length therewith, said flanges gradually decreasing in height from the center of the plate portion toward either end thereof, an attaching device comprising spaced side arms, and means pivotally connecting the slide intermediate its ends to and between the side arms of the attaching device.

In testimony whereof I hereunto affix my signature.

JOHN B. BAXTER.
